UNITED STATES PATENT OFFICE.

JAMES CAREY DAVIS, OF CHICAGO, ILLINOIS.

APPARATUS FOR TEMPERING.

Original application filed October 24, 1923, Serial No. 670,486. Divided and this application filed June 18, 1924. Serial No. 720,726.

To all whom it may concern:

Be it known that I, JAMES CAREY DAVIS, a citizen of the United States, and a resident of Chicago, in the county of Cook and State of Illinois, have invented certain new and useful Improvements in Apparatus for Tempering, of which the following is a specification.

My present invention relates to the art 10 of tempering in general, more particularly to the tempering of metal and specifically to the localized hardening of steel castings containing a modifying agent. Broadly considered, the invention comprehends an improved method for tempering, an apparatus for carrying out the tempering method, and the resultant improved product. The said improved method and the resultant improved product are included within the subject matter 15 of my co-pending application for Letters Patent filed October 24, 1923, Serial No. 670,486, of which the present case is a division.

While the invention has a broad field of 20 usefulness for changing the state of various articles of different composition, I have found it of peculiar utility for producing cast steel car wheels containing manganese as a modifying agent and I, therefore, find it convenient to describe the invention in 25 connection with such a product, it being understood that such limited field of specific description is employed purely for purposes of an example of the utility of the invention 30 in its several phases.

The principal objects of the present invention are the provision of an improved method of tempering; the provision of an improved apparatus for tempering; the provision of an improved tempered product; the provision of a method of tempering characterized by a localization of the tempering; the provision of a method of tempering wherein the area of the tempering may be substantially controlled within predetermined limits; the provision of a method of tempering characterized by the direction of fluid upon predetermined parts only of the article to be tempered; the provision of a method of tempering characterized by a differential or progressive tempering of the article; the provision of a method of tempering characterized by the employment of means to prevent action of the tempering 35 steps upon such parts of the article as it is not desired to modify; the provision of a method of tempering characterized by so placing the surfaces to be tempered and so carrying out the steps of tempering that certain parts of the article upon which the operation is performed are left unchanged, the provision of a method of tempering characterized by the directing of a treating fluid upon the article to be tempered, in general, and, in particular, means for directing such fluid upon the precise area desired to be acted upon; the provision of a method of tempering characterized by the employment of a plurality of streams of different volume or intensity whereby areas of the article may be tempered differentially; the provision of a method of tempering characterized by the provision of means whereby the article may be subjected to equivalent amounts of treating fluid at all predetermined points so that a substantial uniformity of tempering may be attained; the provision of an improved apparatus for carrying out the several objects set forth; the provision of a tempering apparatus characterized by means for a localization of the tempering, in general, and more particularly, means whereby the area of tempering may be substantially limited; the provision of tempering apparatus characterized by the provision of means for ejecting the tempering fluid upon a predetermined point or points in general, and, in particular, by the employment of a plurality of ejector members so arranged that the article may be tempered differentially or progressively and thus predetermined varying qualities imparted thereto; the provision in a tempering apparatus of means for preventing tempering action upon the parts of the article 45 which it is not desired to change; the provision of a tempering apparatus characterized by the horizontal ejection of the tempering fluid so that parts of the object may remain unmodified; the provision of a tempering apparatus characterized by the employment of a plurality of series of streams of tempering fluid, in general, and in particular, one wherein the volumes of fluid of the several streams differ and thus the 50 action thereof may be varied differentially and progressively; the provision of a tempering apparatus characterized by the em-

ployment of a shield protecting the article acted upon from the action of the tempering fluid, and the provision of an improved means for operating such shield, together with such further objects, benefits and advantages as may hereinafter appear or may be pointed out.

In the attainments of the foregoing objects and certain additional benefits and advantages to be hereinafter disclosed, I find it convenient to carry out my improved method by means of an apparatus, one embodiment of which is illustrated in the accompanying drawings.

On inspection of these drawings it will be observed that, as above suggested, I have for purposes of convenience in disclosure and description, illustrated an apparatus of a form adapted for the treatment of a disc-like metallic casting, to wit: in the present case, a flanged cast manganese-steel wheel. The invention is peculiarly adapted for the treatment of such objects, as will be manifest when it is considered that a great desideratum in the hardening of wheel treads is that such hardening be both uniform in order that the wheel may wear uniformly in service, and not become out-of-round, and at the same time that the hardening be localized to that portion of the tread and throat which is most usually in contact with the rail head, in order that the rim of the wheel may wear uniformly and not become grooved in service. To this end, therefore, it is most desirable that the flange of the wheel which ordinarily is of quite sufficient hardness without tempering be not further hardened, and similarly, that the outer marginal portion of the tread which is opposite to the flange and receives much less wear, owing to its relatively less contact with the rail head, be left unmodified and relatively soft so that the wheel tread in service will wear down uniformly. It is likewise desirable that the web and center of the wheel be left free from hardening and in their relatively soft state.

In the accompanying drawings—

Figure 1 is a plan view of the tempering apparatus;

Figure 2 is a sectional view taken on the line II—II of Figure 1, the wheel being shown therein in elevation;

Figure 3 is a fragmentary sectional plan view of the part of the apparatus in Figure 1; and

Figure 4 is a transverse sectional view of the wheel tread.

Referring first more particularly to Figures 1 and 2 of the drawings it will be observed that the tempering apparatus here shown comprises an elliptically formed casing 10 provided with a chamber 11 having connections to sources of fluid 12, baffle plates 10^a being disposed in said casing 10

adjacent the inlets 13 of the fluid connections 12, in order to prevent surging of the fluid through the adjacent jets shortly to be described. The baffle plates 10^a are provided with suitable ports 14 for the equalization of fluid pressure within said casing 10, to the end that the discharge through the several jets may be substantially uniform, and clean-cut openings above inlets are provided, with closing plugs 13^a.

In order that, where desired, as in the case of a wheel tread, the article acted upon may be tempered uniformly, I find it convenient to impart to the chamber 15 within the casing 10 a contour corresponding in general to that of such article, thus in the present case, since a wheel tread is to be acted upon, the chamber 15 is annular.

For directing fluid from the chamber 11 of the casing 10 to the surface to be treated, in the present instance the tread 16 of the wheel 17, I employ a number of streams or jets of fluid which are conveniently given the desired direction by means of nozzles 18. The latter, as will be apparent on viewing Figure 1, are preferably arranged radially and directed towards the center of the wheel, which is to be carefully centered in the casing 10 and may be sustained by the supporting members 19. As will be seen on viewing Figure 2, the nozzles 18 are preferably arranged in a plurality of series 20, 21, 22. In the present case inasmuch as the object is to harden the throat 23 and tread 16 of the wheel, I find it desirable to eject the largest quantity of fluid through the nozzle series 20, a lesser quantity through the nozzle series 21 and the least quantity through the nozzle series 22. To this end the series 20 contains the largest number of nozzles and the series 21 and 22 progressively less numbers thereof.

At various times and for various purposes, and especially in the present case of a wheel tread it is desirable to preserve a certain part of the article acted upon from the tempering action of the fluid streams emitted from the jet series 20, 21, 22. For the accomplishment of this purpose I have provided the shield 24, which when used for protecting an article which is circular in cross section may be a band of springy metal such as is indicated at 24 (Figure 3). One end of this band 25 may be attached to a crank arm 26, the opposite end of the band 27 passing through a stirrup 28 on such arm 26 may be attached to the casing 10 at a convenient point such as indicated at 29.

For the purpose of contracting the band 24 upon the article to be treated, e. g. the wheel 17, an operating lever 30 connected by the link 31 to the arm 26, may be employed. To facilitate one action of the shield, e. g. its contraction, a tension spring

32 having a suitable connection to the exterior of the casing at a convenient point such as is indicated at 33, may be utilized.

From the foregoing description of my improved method of an apparatus for tempering, it will be perceived that the resultant product may be tempered as desired, that such tempering may be localized, that such tempering may be uniform, as for example, 10 in belts around a cylindrical object such as a wheel tread, and that by its use belts of differing hardness may be produced, such as those indicated by the index numbers, according to the Brinell hardness scale appearing on the inner periphery, the flange, the throat, the tread 16 and the outer periphery 34 of the wheel whose contour in cross-section is outlined in Figure 4, and all this without affecting such parts as may be 15 desirably left unchanged.

Other advantages and uses of my present invention will occur to those who are skilled in the art.

Having thus described my invention and 25 illustrated its use, what I claim as new and desire to secure by Letters Patent is:

1. A tempering apparatus comprising, in combination, a source of tempering fluid, and means for directing a plurality of 30 streams of fluid of different volume from such source upon the article to be tempered.

2. A tempering apparatus comprising, in combination, a source of tempering fluid, and means for directing a plurality of series 35 of streams or currents of fluid of different volume from such source upon the article to be tempered.

3. A tempering apparatus comprising, in combination, a source of tempering fluid, 40 and means for directing a plurality of streams or currents of fluid of different volume from such source upon the article to be tempered, one of said streams being above another thereof.

4. A tempering apparatus comprising, in combination, a source of tempering fluid, and means for directing a plurality of series of streams of fluid from such source 50 upon the article to be tempered, one of said series being above another thereof, and having a larger volume.

5. A tempering apparatus comprising, in combination, a source of tempering fluid, and means for directing said fluid upon an 55 article to strike it in distinct layers.

6. A tempering apparatus for car wheels comprising, in combination, a source of tempering fluid, a protecting shield, and means for directing a stream of fluid from 60 such source upon the tread portion of the wheel to be tempered, the shield being arranged to deflect such fluid from other portions of the tread.

7. A tempering apparatus for car wheels 65 comprising, in combination, a source of

tempering fluid, a protecting shield, means for directing a stream of fluid from such source upon the tread portion of the wheel to be tempered, the shield being arranged to deflect such fluid from other portions of the tread subject to the direct effects of the stream and means for causing such shield to follow the contour of the article to be tempered.

8. A tempering apparatus for car wheels 75 comprising, in combination, a source of tempering fluid, a protecting shield, means for directing a stream of fluid from such source upon the tread portion of the wheel to be tempered, the shield being arranged to deflect such fluid from other portions of the tread subject to the direct effects of the stream and means for causing the shield to encircle the article to be tempered.

9. A tempering apparatus, comprising, in combination, a source of tempering fluid, a protecting shield, means for directing a stream of fluid from such source upon a portion of the article to be tempered, the shield being arranged to deflect such fluid away from another portion of such article, and means for contracting such shield upon the article to be tempered.

10. A tempering apparatus comprising, in combination, a source of tempering fluid, 95 a protecting shield, and means for directing a stream of fluid from such source upon a portion of the article to be tempered, the shield being arranged to deflect such fluid away from another portion of such article, and means for contracting such shield upon the article and expanding away therefrom.

11. A tempering apparatus comprising, in combination, a source of tempering fluid, a yieldingly resistently mounted shield, 105 means for directing a stream of fluid from such source upon a portion of the article to be tempered, the shield being arranged to deflect such fluid away from another portion of such article, and means moving such shield.

12. A tempering apparatus comprising, in combination, a source of tempering fluid, a spring actuated protecting shield, means for directing a stream of fluid from such source upon a portion of the article to be tempered, the shield being arranged to deflect such fluid away from another portion of such article, and means for moving such shield against the action of the spring.

13. A tempering apparatus comprising, in combination, a source of tempering fluid, a protecting shield and means for directing a stream of fluid from such source upon a portion of the article to be tempered, the shield being arranged to deflect such fluid away from another portion of such article, and an operating lever for moving such shield towards and away from the article.

14. A tempering apparatus, comprising, 130

in combination, a source of tempering fluid, a protecting shield, means for directing a stream of fluid from such source upon a portion of the article to be tempered, the shield being arranged to deflect such fluid away from another portion of such article, and a yieldingly resistant operating lever for expanding and contracting such shield.

15. A tempering apparatus for car wheels comprising, in combination, a source of tempering fluid and means for directing fluid from such a source upon a restricted portion of the tread of the wheel to be tempered including ejector members.

16. A tempering apparatus for car wheels comprising, in combination, a source of tempering fluid, and means for directing fluid from such source upon a restricted portion of the tread of the wheel to be tempered including a plurality of series of ejector members.

17. A tempering apparatus, comprising, in combination, a source of tempering fluid and means for directing fluid from such source upon the article to be tempered including a plurality of series of ejector members, the top-most series having the largest number of ejector members.

18. A tempering apparatus for car wheels comprising, in combination, a source of tempering fluid, and means for directing fluid from such source upon a restricted portion of the tread of the wheel to be tempered, including ejector members, the

several ejector members being symmetrical- 35
ly arranged with reference to the axis of the apparatus.

19. A tempering apparatus for car wheels comprising, in combination, a source of tempering fluid and means for directing fluid from such source upon a restricted portion of the tread of the wheel to be tempered including ejector members, the several ejector members being concentrically arranged. 40

20. A tempering apparatus comprising, in combination, a source of tempering fluid, and means for directing a plurality of series of streams of fluid from such source upon the article to be tempered, one of said 50 series being above another thereof, and varying in intensity.

21. A tempering apparatus comprising, in combination, a source of tempering fluid and means for directing a plurality of 55 series of streams of fluid from such source upon the article to be tempered, one of said series being above another thereof and varying in intensity so that the gravitational flow of the fluid from the upper streams, 60 plus the flow of the fluid from the lower streams, will impinge a substantially uniform quantity of fluid upon a portion to be tempered.

In testimony whereof I have hereunto 65 signed my name.

JAMES CAREY DAVIS.
